UNITED STATES PATENT OFFICE.

CYRUS D. BYERS, OF WOODWARD, IOWA, ASSIGNOR TO STANDARD OIL COMPANY, OF DES MOINES, IOWA, A CORPORATION OF INDIANA.

UNLOADING APPARATUS FOR PORTABLE TANKS.

1,199,739.

Specification of Letters Patent. Patented Sept. 26, 1916.

Application filed January 19, 1916. Serial No. 73,035.

To all whom it may concern:

Be it known that I, Cyrus D. Byers, a citizen of the United States, residing at Woodward, in the county of Dallas and State of Iowa, have invented a new and useful Improvement in Unloading Apparatus for Portable Tanks, of which the following is a specification.

My invention relates to certain new and useful improvements in liquid unloading devices for portable tanks.

The object of the invention is to provide an unloading apparatus of the utmost simplicity and which is proof against tampering by unauthorized persons. With these and other objects in view, as will more fully appear hereafter, I have designed the form of apparatus illustrated by the accompanying drawings in which:

26 Figure 1 is a side elevation of my improved apparatus in operative position above a tank-car which is to be unloaded. Fig. 2 is a face view of the central portion of the mast, showing the means for locking the tilting arm in its inoperative position. Fig. 3 is a front elevation, (from the track side) showing the device in its inoperative position. Fig. 4 is a detail section showing the connections between the tilting arm and the 25 detachable suction pipe. Fig. 5 is a detail section showing the connections between the tilting arm and the mast, and Fig. 6 is a section on the line 6 of Fig. 1, showing the tie for the mast members.

35 Referring more particularly to the drawings, the numerals 10 designate the two vertical mast members of my apparatus, these members being preferably constructed of tubing and mounted in a concrete base 11. The third mast member, designated 12, may also be conveniently constructed of tubing and arranged at an inclination to the vertical mast members, being mounted in a separate concrete base 13 and secured at its upper end just below the upper ends of the vertical mast members 10 by a T-pipe 14. When arranged in the manner described, the mast sections 10 and 12 form a triangular structure of great strength and rigidity but 45 of light weight and simple construction. Intermediate the length of the mast the three members which make up the same may be tied together as by a triangular brace 15, shown in Fig. 6. At their upper ends the 50 vertical mast members 10 are provided with

inwardly turned opposed elbows 16 carrying glands 17 in which are mounted the hollow horizontal trunnions 18 for the tilting arm, the connections being shown in Fig. 5. Extending forwardly and rearwardly from 50 the hollow trunnions 18 are two pipe sections 19 which make up the tilting arm of my apparatus, each of the pipe sections being in communication with one of the trunnions 18 and through it with the corresponding hollow mast member 10, and the two pipe sections being joined at both ends as by cross-bars 20. At their forward ends the respective sections 19 of the tilting arm are provided with out-turned elbows and nipples 60 which carry swivels 21 for the depending suction pipes 22, the connections being illustrated in Fig. 4. At their rear ends, that is, back of the trunnions 18, the pipe sections 19 are bent upwardly, as shown at 23, 70 and a chain 24 is connected to the rear tie bar 20 and leads downwardly to an eye 25 in the inclined mast member 12, as shown in Fig. 1. Below the eye 25, the mast member 12 carries a second eye 26, which may be 80 conveniently formed as one of the securing means for the triangular brace 15, shown in Fig. 6, and on this eye 26 there is secured a swinging hasp member 27, which is adapted to lock the tilting arm in its vertical or inoperative position as will later appear. Adjacent its lower end each of the vertical mast sections 10 is provided with a T 28 into which is tapped a pipe line 29 leading to a pump and storage tank. 90

In the arrangement shown in Fig. 1, the unloading apparatus is situated in operative relation to a railroad siding 30 so as to unload a tank car 31 thereon.

Assuming that the parts occupy the positions shown in Fig. 1, the operation of my apparatus is as follows: A suction pump being connected to each of the pipes 29, the oil from the tank car will enter the depending suction pipes 22, passing up the latter 100 into the pipe sections 19 of the tilting arm, thence through the hollow trunnions 18 and mast members 10 and out through the pipes 29 to the pump and storage reservoir. It will be understood that tank cars as commonly constructed have their tanks divided for carrying separately two different grades of oil, for instance, gasoline and lubricating oil. One of the suction pipes 22 will in that event enter each of the compartments of the 110

tank car, and the two fluids may be pumped out simultaneously, one through one section of the tilting arm and one mast member and its connection pipe 29, and the other through the opposite side of the unloading apparatus.

When the tank car has been emptied, the operator may from the ground reach the chain 24 and by pulling on the same may tilt the pipe sections 19 of the tilting arm, bringing the latter into the vertical position shown in Fig. 3. In this vertical position of the tilting arm, the rear cross-bar 20 thereof will lie against the face of the inclined mast section 12 between the eyes 25 and 26. The hasp 27 may therefore be swung over this cross-bar to engage the eye 25, and if a padlock be then engaged with this eye the parts may be simply and securely locked in inoperative position as shown in Fig. 2.

Although I have shown and described in considerable detail one specific embodiment of my invention, it is to be understood that this showing and description is illustrative only, and for the purpose of making my invention more clear, and that I do not regard the invention as limited to these details, nor to any of them, except in so far as I have included such limitations within the terms of the following claims, in which it is my intention to claim all novelty inherent in my invention as broadly as is possible in view of the prior art.

What I claim as new and desire to secure by Letters Patent is:—

1. An unloading apparatus for portable tanks, comprising a stationary mast, including a fluid conduit member, a tilting arm mounted to rock upon the mast and including a fluid conduit member, and a depending suction conduit member carried by the arm to enter a tank positioned beneath the same, all of said parts being normally in open communication with each other.

2. An unloading apparatus for portable tanks, comprising a stationary mast, including a fluid conduit member, a tilting arm mounted to rock upon the mast and including a fluid conduit member, a depending suction conduit member carried by the said arm to enter a tank positioned beneath the same, all of said parts being normally in

open communication with each other, and means for locking said tilting arm in a vertical position.

3. An unloading apparatus for portable tanks, comprising a stationary tubular mast, a tubular tilting arm mounted to rock upon the mast, and a tubular depending suction member carried by said arm to enter a tank positioned beneath the same, all of said parts being normally in open communication with each other.

4. An unloading apparatus for portable tanks, comprising a tubular mast member, a hollow trunnion communicating with the bore of said mast member and mounted to rock thereon, a tubular tilting arm carried by said hollow trunnion, and a depending suction member carried by the arm to enter a tank positioned beneath the same, all of said parts being normally in open communication with each other.

5. An unloading apparatus for portable tanks, comprising a pair of spaced parallel tubular mast members, hollow trunnions carried thereby, a tilting arm mounted upon the said hollow trunnions and comprising a pair of parallel tubular members each in communication with one of said trunnions and the corresponding mast member, and a depending suction member carried by each of said tubular arm members to enter a tank positioned beneath the same.

6. An unloading apparatus for portable tanks, comprising three tubular mast members spaced apart at their lower ends and connected at their upper ends, a pair of hollow trunnions carried by two of said mast members, a tilting arm carried by and extending on both sides of said trunnions and having tubular sections in communication therewith, depending suction members carried by the said tubular sections at one end and adapted to enter a tank positioned beneath the same, and means for locking the opposite end of said arm to said mast to maintain the arm in vertical position.

CYRUS D. BYERS.
